UNITED STATES PATENT OFFICE.

RICHARD S. GIESE, OF PITTSBURGH, PENNSYLVANIA.

ELECTRIC-LIGHT FIXTURE.

1,195,805.

Specification of Letters Patent. Patented Aug. 22, 1916.

Application filed April 8, 1916. Serial No. 89,844.

To all whom it may concern:

Be it known that I, RICHARD S. GIESE, a citizen of the United States, residing at Pittsburgh, in the county of Allegheny and 5 State of Pennsylvania, have invented a new and useful Electric-Light Fixture, of which the following is a specification.

This invention has reference to electric light fixtures and its object is to provide a 10 combination semi-indirect and shower fixture in which metallic parts are reduced to a minimum.

In accordance with the present invention there is provided a dish or bowl of the general character employed in semi-indirect lighting but modified in structure to adapt 15 it to the purposes of the present invention, and such bowl is utilized as a spreader for the shower lights while the shower devices 20 are employed as the supporting means for the dish or bowl. In this manner all metallic rings or other supports customarily employed to sustain the dish or bowl of the semi-indirect side of the fixture are avoided, 25 and the only metallic parts employed are the customary sockets for the lighting bulbs of the shower, chains carrying the bulbs, and the customary shade-holders supporting shades such as are used in connection with 30 single lamp bulbs, such shades forming the sole support for the dish or bowl.

The invention will be best understood from a consideration of the following detailed description, taken in connection with 35 the accompanying drawings forming part of this specification, with the further understanding that while the drawings show a practical form of the invention, the latter is not confined to any strict conformity with 40 the showing of the drawings, but may be changed and modified so long as such changes and modifications come within the scope of the appended claims.

In the drawings:—Figure 1 is a perspective view of the fixture of the present invention as viewed from below the level of the fixture. Fig. 2 is a diametric vertical section on a larger scale than Fig. 1, the section being taken through one of the shower elements. Fig. 3 is a top plan view of the fixture of Fig. 1, omitting the supporting chains.

Referring to the drawings, there are shown ordinary electric lamp sockets 1 de-

signed to receive and carry lamp bulbs 2 of 55 the customary incandescent type, and these sockets are each provided with a shade supporting ring 3, which may be of the type having shade-engaging set screws 4.

In shower lights it is customary to employ 60 elongated shades quite closely surrounding the lamp bulbs, and such shades are indicated in the drawing at 5. Each shade is provided with a neck 6, which where joining the body of the shade forms a shoulder 7. 65 Each socket 1 is provided with a suspension ring 8 which may be of standard or special construction and arranged for the passage of the usual conductor 9 and the reception of a suspension chain 10 of the character ordinarily employed in electric light fixtures. The chains 10 in the installed fixtures are carried to a ceiling canopy and there secured in the customary manner, but as this is the 70 common practice in the installation of 75 shower and other lighting fixtures, it is not deemed necessary to show it.

Shower electric lighting fixtures are often provided with a spreader for the shower lights in the form of a plate or dish of ornamental configuration, which dish is suspended by chains, such as the chains 10, while sockets, such as sockets 1, are installed in the dish or plate to receive the bulb, such sockets being sometimes suspended from the dish 85 or plate by short chains.

By the present invention there is provided a dish or bowl 11 of glass or other suitable material usually of a translucent nature, that is, the glass or other material is of a 90 character to transmit light diffusively while the inner wall of the dish is made reflecting for the purpose of directing light against the ceiling of the room or compartment in which the fixture is installed. This is the usual 95 practice in semi-indirect lighting, and with the fixture of the present invention there is provided a lamp socket 12 designed to carry an electric light bulb 13, the socket being suspended by a customary conductor cord 100 14 depending from the usual canopy supporting the fixture, but which canopy is not shown in the drawings.

The dish or bowl 11 has its rounded or generally convex face directed downwardly, 105 so that the hollow interior of the dish is toward the ceiling and at the elevation at which the fixture is usually placed the bowl

completely hides the lamp bulb 13 from observation. The dish 11 has upstanding sides 15 usually provided at the upper edge with a flange 16 serving as an ornamental finish. 5 The central portion of the dish has a drop bulge 17 merging into a substantially flat part 18 between the bulge and the upstanding side walls 15. It is not necessary that the parts of the dish be shaped as indicated in 10 the drawings, for such shape may vary considerably from the shape shown while still performing the functions desired. The substantially flat portion 18 is pierced at intervals by passages 19 of a size to admit the 15 necks 6 of the shades 5 through them with the portions of the dish immediately surrounding the passages 16 resting on the shoulders 7. These shades, therefore, serve as supports and constitute the sole supports 20 for the dish 11. At the same time the disposition of the passages 19 is such that the dish 11 serves as a spreader for the direct lighting elements of the shower. The result is that the sole supporting means for the entire fixture consists of the chains 10 each of 25 which carries a socket 1 individual thereto, and these chains are the only metallic parts needed for the suspension of the entire fixture from the usual ceiling canopy, (not 30 shown).

The bulge 17, which extends downwardly in the installed position of the fixture, is designed to partly house the lamp bulb 13, so that the source of indirect lighting represented by the bulb 13 is partly within the 35 bulge 17, thus increasing the light transmitted through the dish toward the floor of the compartment to be illuminated, while reflections from the inner surface of the dish 40 toward the ceiling cause the lighting up of the latter and the distribution of the light throughout the room.

Direct lighting is obtained from the bulbs 2 with the light more or less confined and 45 concentrated by the shades 5 to an area below the fixture.

By suitably installing the electric circuits to the fixture, the bulbs 2 may be energized separately from the bulb 13, so that the fixture 50 may be used either as a direct fixture or as a semi-indirect fixture, or the two styles of lighting may be employed at one time.

By the present invention the benefits of both direct and semi-indirect lighting are 55 obtained with a minimum of metal in the fixture, and with the elimination of more or less unsightly and shadow-casting parts.

The fixture also has the advantage of economical construction, for certain parts 60 such as the sockets 1, heretofore employed in such fixtures solely to carry the direct lighting members, are utilized in the present fixture as the supporting means for the indirect lighting side of the fixture, that is, the 65 dish 11.

The shower lights are shown in the drawings as three in number, but it will be understood that any suitable number of such lights may be employed, and usually such lights are distributed evenly about the fixture. 70

What is claimed is:

1. An electric light fixture provided with shower lights each having supporting means individual thereto, and a semi-indirect lighting dish or bowl carried directly and solely 75 by the shower lights.

2. An electric light fixture comprising a plurality of electric lamp sockets and suspension devices therefor, shades for the sockets, and a semi-indirect lighting dish 80 having passages therethrough for the shades and resting on and supported solely by said shades.

3. An electric light fixture comprising a plurality of electric lamp sockets, shades and 85 shade holders therefor, suspension means connected to the sockets, and a semi-indirect lighting dish having passages therethrough for the necks of the shades and resting upon and supported by the shades, said dish serving as a spreader for the sockets and shades to constitute the fixture a combined shower and semi-indirect fixture. 90

4. An electric light fixture provided with a plurality of electric lamp sockets, shades 95 and shade holders therefor, suspension means connected to the sockets, and a semi-indirect lighting dish having upstanding sides, a central hollow depression, and substantially flat portions between the central 100 depression and the sides, said flat portion having passages therethrough distributed about it for the necks of the shades, the dish resting upon and being supported by the shades, whereby the fixture constitutes a 105 combined shower and semi-indirect lighting fixture.

5. In an electric light fixture of the combined shower and semi-indirect type, a semi-indirect lighting dish having upstanding 110 marginal portions, a central hollow depression, and a substantially flat portion surrounding the hollow depression and merging into the upstanding sides, the flat portion having passages therethrough distributed circumferentially about the central depression. 115

6. A combined shower and semi-indirect electric light fixture, comprising a semi-indirect dish or bowl, and shower lights extending through and below the bowl and provided with supporting means, the shower lights constituting the sole support for the dish. 120

7. An electric light fixture provided with 125 shower lights each having suspension means connected and individual thereto and constituting the sole suspension means for the entire fixture, and a spreader for the shower lights and the suspension means, compris- 130

ing a semi-indirect lighting dish or bowl directly engaging and carried solely by the shower lights.

8. A combined direct and semi-indirect lighting fixture provided with separate direct lighting means, a separate suspension means for each direct lighting means, a spreader for the separate direct lighting means, comprising a semi-indirect lighting dish or bowl directly engaging the direct lighting means, and means for supporting light producing means in operative relation to the dish or bowl to direct light through the bowl and for the reflection of light from the bowl to produce indirect lighting effects.
- 10 9. A combined direct and semi-indirect

lighting fixture comprising a semi-indirect dish or bowl, and a series of separate shower lights extending through and below the bowl within the margins thereof and each provided with a suspension means individual thereto, the bowl constituting a spreader for the suspension means and said suspension means constituting the supporting means for the fixture.

20 In testimony, that I claim the foregoing as my own, I have hereto affixed my signature in the presence of two witnesses.
